UNITED STATES PATENT OFFICE.

WALTER M. PAULSON AND AXEL M. WALSTROM, OF MINNEAPOLIS, MINNESOTA, ASSIGNEES TO THE CREAMERY PACKAGE MFG. COMPANY, OF CHICAGO, ILLINOIS, A CORPORATION OF ILLINOIS.

MACHINE FOR MAKING TUBS AND THE LIKE.

Application filed December 9, 1922. Serial No. 605,796.

To all whom it may concern:

Be it known that we, WALTER M. PAULSON and AXEL M. WALSTROM, citizens of the United States, residing at Minneapolis, in 5 the county of Hennepin and the State of Minnesota, have invented certain new and useful Improvements in Machines for Making Tubs and the like, of which the following is a specification.

10 The invention relates to machinery employed in the manufacture of tubs, pails and like containers of stave construction, and more particularly to a machine for seating the bottoms and the chime hoops in such 15 containers.

Tubs, as exemplified in those used in the packing of butter, commonly comprise an assembled stave structure, having an inset bottom supported in an internal groove or 20 croze, and bound by hoops. In the manufacture of the tubs, the insertion of the bottoms within the trussed staves and the attachment of the bottom or chime hoops heretofore have involved difficult and costly 25 hand operations and frequent damage to the tubs.

It is the primary object of this invention to provide an efficient durable machine, operable upon tubs, pails, and like containers 30 of stave construction, for automatically assembling the bottoms and chime hoops with the staves, thereby accomplishing a substantially reduced cost and a uniform quality in the product.

35 Further objects include the provision in such a machine of automatic mechanisms for securing the tub or other container in position to be operated upon, for relatively positioning the parts to be assembled, for 40 inserting the bottom in its supporting croze, and for placing a hoop over the chime ends of the staves.

45 Other objects and advantages will be apparent in the following detailed description of a preferred embodiment of our invention, which we have selected for illustration in the accompanying drawings. It will be understood, however, that various changes in form construction and arrangement may be 50 made by those skilled in the art without departing from the spirit and scope of the invention as expressed in the appended claims.

Referring to the drawings, Fig. 1 repre-

sents a side elevation of the machine. Fig. 2 is an elevation of the delivery end. Fig. 3 55 is a longitudinal sectional elevation. Fig. 4 is a cross sectional elevation viewed from the receiving end. Fig. 5 is a sectional partial plan taken on the plane of the line 5—5 in Fig. 2. Fig. 6 is a view of the underside of 60 the clamping mechanism as seen from the plane of the line 6—6 in Fig. 2. Fig. 7 is a detail section of a portion of the clamping and hoop driving mechanism. Fig. 8 is a 65 plan view of the hoop carrier, and Fig. 9 is a fragmentary sectional view of the latter.

Stated generally the operative arrangement of the machine, herein illustrated as 70 adapted to the making of butter tubs, comprises a horizontal support or table upon which the bottomless tubs are successively deposited in inverted position, with a loose bottom piece laid on the table within the inverted larger top end of the tub.

At this stage of manufacture of a tub, the 75 component staves have been assembled within temporary truss rings, the tub ends have been trued and finished, and the internal bottom-supporting groove or croze has been 80 cut, after which the temporary truss rings have been removed except the one uppermost. The bottoms have been made and their edges finished for engagement with the croze when assembled with the staves.

85 For the purpose of this description, the assembly of staves, exclusive of the bottom, is referred to hereinafter as the drum, and is intended to designate that part in a tub or other container of stave construction.

90 As each tub or like container is placed on the table, a device carrying a chime hoop is deposited on the inverted bottom end of the drum. A reciprocating conveyor slides the drums and the enclosed loose bottoms successively over a pair of vertically operable plungers or elevating plates, whereupon locking means engages the remaining truss ring of the positioned drum and secures it to the table. The loose bottom is then automatically centered in relation to the drum, after which the plungers rise and force the bottom upward through the converging staves until seated in the croze, the untrussed portions of the staves resiliently 95 separating to permit passage of the bottom.

Simultaneously a clamping head descends upon the drum, and with the seating of the bottom operates to compress the stave ends thereabout and force the chime hoop from its carrying device over and upon the stave ends. The tub is then released and moved out by the conveyor.

More specifically described, with reference to the drawings, the numerals 1 and 2 indicate a pair of spaced side members suitably connected, as by the cross members 3, to form a frame. Supported upon the cross members 3 are a pair of spaced rails 4 extending longitudinally outward from each end of the frame to form respectively a receiving table and a delivery table for the tubs. Lateral guides 5 serve to position the tubs laterally on the rails.

Operating between the spaced rails 4 is a conveyor for moving the tubs longitudinally through the machine and comprising a reciprocating feed bar 6, having its end at the receiving end of the rails turned up to form a drum engaging dog 7, and carrying other spring-pressed dogs 8 positioned to successively engage and progressively advance the tubs along the rails 4. The rear end of the feed bar 6 is secured to a cross bar 9 slidably supported at its ends beneath the rails 4 upon ways 10.

The feed bar 6 is longitudinally reciprocated by means of a pair of levers 11 and 12 connected by the links 13 and 14 with the cross bar 9. A rock shaft 15, journaled in the frame members 1 and 2 and extending therethrough, carries at each end a flanged collar 16 and 17 to which are respectively secured the levers 11 and 12 for pivotal movement. The levers are operated by a pair of connecting rods 18 and 19 having slot bearings engaging the crank pins 20 and 21 carried by a pair of gears 22 and 23 mounted on a shaft 24 journaled in the upper portions of the frame members 1 and 2. A pair of pinions 25 and 26 in driving mesh with the gears 22 and 23 are carried by a shaft 27 journaled in the frame members and carrying also a drive pulley 28 connected with a source of power, as by belting 29. The connecting rod slot bearing imparts intermittent movement to the feed bar 6, thereby permitting the bottom seating and stave clamping mechanisms to be disengaged before advancing the tubs.

As the tubs are moved from the receiving end of the rails to the first and operating position, the loose bottoms are pushed along by the rear edge of the inverted top of the enclosing drum. Being of less diameter than the inverted drum top, the tub bottom is not in centered relation thereto but is in contact with the staves at the rearward side. If raised from this position, friction with the staves is likely to tilt the bottom and cause it to be jammed or broken.

To overcome this difficulty, we have provided an auxiliary feed or bottom centering device which, as the drum approaches the end of its movement, accelerates the advance of the bottom until drum and bottom come to rest in relatively concentric relation.

Suitably supported beneath the rails 4 and located centrally of the operating position of the tubs, is a pair of spaced brackets 30 carrying a shaft 31. A pair of spaced centering bars 32 are intermediately pivoted on the shaft 31 with their upper serrated ends extending laterally of and above the feed bar 6. A spring 33, attached to a cross connection between the lower ends of the bars 32 and having a stationary attachment to a cross member of the frame, normally maintains the upper ends of the bars 32 inclined toward the receiving end of the machine.

A cross connection 34 between the upper ends of the centering bars is positioned above the feed bar 6. As the feed bar approaches the end of its tub-advancing movement, a lug 35 carried thereby engages the member 34 and swings the serrated ends of the centering bars upwardly and rearwardly into contact with the underside of the tub bottom. The relatively greater speed of the serrated ends of the pivoted centering bars effects an accelerated advance of the bottom, so that at the end of the stroke of the feed bar the bottom is in centered position. The bottom is raised before the return stroke of the feed and centering bars.

Upon the positioning of the drum and bottom as described, the bottom raising and drum locking mechanisms become operative. At this position of the tub the underlying rails 4 are laterally recessed to provide a preferably circular opening 36 between the rails of somewhat less diameter than of the inverted tub top. Positioned in the recess 36 and flush with the tops of the rails 4 is a pair of substantially semicircular elevating plates 37 and 38 disposed at each side of the feed and centering bars.

Each of the elevating plates is operatively supported upon a pair of vertically disposed rods 39 and 40 having their lower ends rigidly mounted in a vertically reciprocating cross head 41. The latter is in sliding engagement at its ends with a pair of vertically arranged guide bars 42 and 43 rigidly supported at their upper ends and intermediate portions in the frame members 1 and 2. Pivotally connected to the outer ends of the cross head 41 is a pair of connecting rods 44 and 45, having slot bearings at their upper ends engaging the crank pins 20 and 21 carried by the gears 22 and 23. The slot bearings permit the cross head and elevating plates to remain at rest in lowermost position during approximately a half revolution of the gears 22 and 23, in which interval the movement of the tubs is accomplished.

Laterally pivoted at each end of the cross head 41 are pairs of rollers 46 and 47 positioned to engage the pairs of bent levers 48 and 49 pivotally supported on the collars 50 and 51 loosely mounted on the guide rods 42 and 43. The upper ends of the pairs of levers 48 and 49 extend inwardly above the rails 4, and are respectively joined to form a yoke or cross connection 52. Movement 10 on the guide rods of the loose supporting collars 50 and 51 is limited by the upper and lower stop collars 52 and 53 stationarily secured to the rods. Springs 54, having stationary frame attachment and connected respectively to each of the levers 48 and 49 outwardly of their pivots, normally maintain the loose collars in lowermost position and the yoke portions 52 of the levers in raised position.

20 The bent levers 48 and 49 serve to lock the drum in position upon the rails 4 while the bottom is being elevated and forced between the converged portions of the staves into its final seat in the croze. As the cross head 41 rises the rollers 46 and 47 engage the inclined lower ends of the levers, forcing them outward and thereby bringing the inwardly extending yoke sections 52 down upon the truss ring 55 and securely 25 clamping the drum to the rails. The further movement of the levers raises the collars 50 and 51 against the tension of the springs 54, the latter compensating for any variation in the location of the truss ring on successive drums. Upon lowering the cross head after the bottom is seated, the locking levers are retracted by the spring tension to release the tub.

30 The hoop carrier, deposited on the upper turned bottom ends of the drums as the latter are placed on the receiving table, is a self centering device comprising a resiliently contractable split ring 56 (Figs. 8 and 9) having a tapered outer periphery adapted to receive and hold a chime hoop as illustrated at 57. Positioned within the ring 56 is a resiliently contractable band 58 lying against the inner periphery of the ring and supported on several retaining guide pins 59 secured in the ring and passing freely through the band. The ends of the band 58 are turned inwardly in spaced relation as at 60, preferably with a compression spring 61 confined therebetween tending to maintain contact between band and ring. The lower edge of the band extends substantially below the ring, serving to enter within the drum end and position the ring in abutment with the ends of the staves.

60 Having placed a hoop over the ring, the band ends 60 may be pinched together and the whole device readily set in position on the drum, the released band maintaining the ring and hoop in centered relation to the stave ends. As hereinafter described, the

hoop is forced downwardly from the ring over the staves, the ring and band contracting to permit the passage therefrom of the tapered hoop.

The chime hoop affixing mechanism is carried mainly by a vertically reciprocable cross head 62 having end bearings operatively engaging the upper portions of the guide rods 42 and 43 as at 63 and 64. Bearing blocks 65 and 66, fixed to the flanged end bearings 63 and 64 of the cross head 62, extend downward in sliding engagement with the guide rods, and carry each a pivot pin 67. Connected to the latter are a pair of connecting rods 68 and 69 extending upward into driven engagement with a pair of eccentrics 70 and 71 mounted on the shaft 24 and preferably secured to the gears 22 and 23 as by bolts 72.

Supported on the underside of the cross head 62 is a clamping head adapted to embrace the inverted bottom ends of the drums, compress the staves after insertion of the bottoms, and drive the chime hoops into place upon the tubs. The clamping head comprises a center plate 73 secured to the cross head and carrying an annular segmental series of radially movable jaws, 74. Each of the segmental jaws is provided with a radial slot 75 in the portion underlying the plate 73 (Fig. 7) through which passes a bolt 76 secured in the plate 73 and carrying a supporting washer 77 permitting sliding movement of the segment. Springs 78, confined between the bolts 76 and the outer ends of the slots 75 tend to force the several jaws radially outward.

The jaws 74 are constructed with depending angularly disposed stave-clamping portions, collectively forming a segmental annular flange adapted to receive and embrace the ends of the staves and a hoop supported thereon. To facilitate entry of the stave ends, the flange is preferably 105 tapered.

Above the tapered inner lower edges of the segments is an annular recess 79 providing space for the chime hoop when the jaws are closed thereupon, and upwardly terminating in a shoulder 80 adapted to engage and drive the hoop from the ring 56 in the downward movement of the head, the preceding stave-contacting portion 81 of the jaws being adapted to compress the staves within the diameter of the chime hoop.

The inward movement of the jaws 74, by which the staves are compressed preparatory to forcing on the chime hoop, is accomplished by means of a vertically slideable ring 82 operatively engaging the tapered lateral periphery of the series of segmental jaws. The ring 82 is supported and operatively controlled by the vertically ex-

- tending pairs of rods 83 and 84, secured in lateral flanges formed on the ring, and passing through guide bearings in the cross head 62. The upper portions of the rods 5 extend above and on opposite sides of the shaft 24, and each carries a sleeve 85 adjustably secured to the rod by upper and lower lock nuts 86, the pairs being bridged at their upper ends by plates 87.
- 10 Mounted at the lower ends of each pair of the sleeves 85 is a cross bracket 88 providing a central bearing for a bar 89 extending between the two brackets and carrying a roller 90 adjacent each of the brackets.
- 15 A pair of cams 91 and 92, rigidly secured on the shaft 24, operate upon revolution of the latter to engage the respective rollers 90 and force downward the rods 83 and 84 and the jaw contracting ring 82. Upon disengagement of the cams, the ring 82 is raised to normal position releasing the clamping jaws 74, by compression springs 93 interposed between the cross head 62 and the lower lock nuts 86. The range of movement 20 of the ring may be adjusted by adjusting the lock nuts 86 to raise or lower the rods 83 and 84 relative to the sleeves 85.

The relative movements of the clamping head as controlled by the eccentrics 70 and 30 71, and of the ring 82 as controlled by the cams 91 and 92, are such that as the clamping head descends upon the inverted drum the ring 82 is relatively in raised position, and the series of jaws 74 is expanded to 35 receive the chime hoop and its carrier and the ends of the staves. Immediately after the completion of the elevating and seating of the tub bottom, as previously described, the cams 91 and 92 engage the rollers 90 and move the ring 82 quickly downward over the descending jaws. This action compresses the staves upon the seated bottom and causes the shoulders 80 in the jaws to 40 engage the upper edge of the chime hoop, whereupon the continued descent of the jaws forces the chime hoop into position 45 upon the ends of the staves. The disengagement of the cams is timed to release the jaws before the upward movement of the 50 clamping head, so that the jaws may be withdrawn freely over the seated chime hoop.

With the completion of the hoop affixing operation, the feed bar 6 becomes operative 55 and moves the tub out of its position beneath the clamping head to the delivery end of the rails 4.

It will now be apparent that we have provided efficient automatic apparatus for the 60 economical and uniform assembling, in tubs and like structures, of the bottoms and chime hoops with the side staves.

We claim as our invention:

1. Apparatus of the class described comprising, in combination, means for support- 65

ing in sliding movement thereon a container drum and a bottom loosely positioned therein, means positioned adjacent the path of said drum for seating said loose bottom therein, and means for applying a hoop 70 upon the bottom end of said drum.

2. Apparatus of the class described comprising, in combination, means for supporting a container drum and a bottom loosely positioned therein, said drum and bottom 75 being slidable upon said support, means operable to secure said drum to said support at one position thereon, means for seating the bottom in said drum, and means for applying a hoop upon the bottom-receiving end of said drum.

3. Apparatus of the class described comprising, in combination, means for intermittently moving a spaced series of up-ended container drums having bottoms 80 loosely positioned therein successively into position to be operated upon, means operable during the periods of rest of said intermittent means to stationarily secure said drums successively in such position, and a plurality of means respectively operable while said drums are so secured to seat said bottoms in their respective drums and to apply end hoops thereto.

4. Apparatus of the class described comprising, in combination, means for supporting in sliding movement thereon an up-ended container drum and a bottom loosely positioned therein, and means positioned adjacent the path of said drum automatically operable to seat said bottom in the end 95 of said drum.

5. Apparatus of the class described comprising, in combination, means for receiving and slidably supporting a container 100 drum having a bottom loosely positioned therein, conveying means for moving said drum into position to be operated upon, means for releasably securing said drum in such position, and means operable to 105 place said bottom in seated engagement with said drum.

6. Apparatus of the class described comprising, in combination, a support for an inverted container drum and a loose bottom positioned therein, said support being adapted for the sliding movement thereupon of said drum and loose bottom, means normally positioned beneath the path of said drum for elevating said bottom into seated engagement with the upper end of said drum, and means for releasably securing said drum in stationary position over said elevating means.

7. Apparatus of the class described comprising, in combination, means for slidably supporting a container drum, means for positioning a bottom in seated engagement with said drum, means carried by said drum for supporting a hoop adjacent the end of 125 130

said drum, and means for applying said hoop upon said drum after the seating of said bottom.

8. Apparatus of the class described comprising, in combination, means for slidably supporting an intermediately trussed assembly of container staves arranged in annular tapering formation, means operable through the larger end of said assembly to force a bottom into seated position in the smaller end of said assembly, releasable means for securing said assembly during the seating of said bottom, independent means removably mountable on said assembly adapted to support a hoop outwardly of the smaller end thereof, and means for compressing said staves about said bottom when seated and thereupon transferring said hoop from said hoop-supporting means into position upon said staves.

9. Apparatus of the class described comprising, in combination, a support, conveying means for intermittently moving a series of assemblies or container staves into successive positions upon said support, means operable in one of said positions to successively insert a bottom in seated relation to the assembled staves, a plurality of means each of which is arranged to support a hoop adjacent one end of one of said assemblies of staves respectively and adapted to be carried thereby, means successively operable to compress said staves about said bottoms when seated and means for successively driving said hoops over the compressed ends of said staves.

10. Apparatus of the class described comprising, in combination, means for slidably supporting a container drum and a loose end closure therefor, said drum being of tapering structure with its smaller end uppermost and enclosing said loose end closure within its supported larger end, means for sliding said drum into position to be operated upon, means for centrally positioning said closure within said drum in such position, and means for elevating said closure into seated engagement with the smaller end portion of said drum.

11. Apparatus of the class described comprising, in combination, a pair of spaced rails forming a support for a container drum and an unattached bottom therefor, said bottom being positioned on said rails within the supported end of said drum, a reciprocatory conveyor operable between said rails to move said drum into successive positions along the rails, a pivoted bar angularly disposed relatively to said conveyor and having one end movable through a path extending above said rails in one of said positions, means on said conveyor adapted to cause said bar in the drum-forwarding movement of said conveyor to swing into engagement with the said bottom and ac-

celerate the movement thereof out of contact with said drum, and means for elevating said bottom into seated engagement with said drum.

12. Apparatus of the class described comprising, in combination, a support for the sliding movement thereon of a container drum having a truss ring thereabout and a loose bottom within said drum, means for elevating said bottom into seated relation to said drum, and means operable by said elevating means adapted to engage said truss ring and secure said drum to said support.

13. Apparatus of the class described comprising, in combination, a support for an assembly of staves, means for releasably securing said assembly of staves to said support, means for seating a bottom within the end portions of said staves, a device carrying a hoop and adapted to be deposited on the ends of said staves, a reciprocatory clamping head having an annular series of normally expanded jaws movable into embracing relation to said stave ends and said hoop, and means for contracting said jaws during the embracing movement of said head to compress said stave ends and cause said jaws to drive said hoop thereupon.

14. Apparatus of the class described comprising, in combination, a support for an assembly of staves, means for seating a bottom within the end portions of said staves, means for supporting a hoop adjacent the ends of said staves, a reciprocatory clamping head having an annular series of normally expanded jaws movable into embracing relation to said stave ends and said hoop, and an independently reciprocatory ring slidably engaging said jaws, said ring being operable to contract said jaws into compressing engagement with said stave ends and driving engagement with said hoop.

15. In apparatus of the class described, in combination, a support for the sliding movement thereon of an inverted bottomless tub or the like and a loose bottom positioned within the tub, an intermittently operable conveyor adapted to move said tub into successive positions on said support, a plunger intermittently operable through said support in one of said positions to seat said bottom in said tub, means associated with said plunger and operable with the upward movement thereof adapted to secure said bottomless tub in said one position, and driving means for alternately operating said conveyor and said plunger.

16. In apparatus of the class described, in combination, a support for a tub drum and a loose bottom therefor, a reciprocatory conveyor bar operable to move said drum and bottom into successive positions on said support, a plunger operable through said

- support in one of said positions to seat said bottom in said drum, a reciprocatory cross head operatively supporting said plunger, means operable by said cross head to secure 5 said drum in said one position, a driven crank, a link having a slot bearing connecting said crank and said cross head, a lever having a connection with said conveyor bar, and a second link having a slot bearing connecting said crank and said lever, said slotted links being relatively angularly disposed and operative to cause the intermittent alternative movement of said drum and said bottom-seating plunger.
- 10 15. 17. In apparatus of the class described, in combination, a support for an inverted bottomless tub or the like having a truss ring thereabout and a loose bottom positioned within the tub, a plunger operable through 20 said support to carry said bottom into seated relation to said tub, a reciprocatory cross head operatively supporting said plunger, and a pivoted lever operable by said crosshead to engage said truss ring and 25 secure said tub to said support during the seating movement of said plunger.
18. In apparatus of the class described, in combination, a support for an inverted bottomless tub or the like having a truss ring 30 thereabout and a loose bottom positioned within the tub, a plunger operable through said support to carry said bottom into seated relation to said tub, a reciprocatory cross head operatively supporting said 35 plunger, a lever operable by said cross head to engage said truss ring, a movable pivot support for said lever, and resilient means for securing said lever in said engagement with said truss ring and thereby resiliently 40 clamp said tub to said first mentioned support during the seating movement of said plunger.
19. In apparatus of the class described in combination, a pair of spaced rails forming 45 a support for an inverted bottomless tub and for a bottom loosely inclosed therein, a reciprocatory bar between said rails having tub engaging dogs operable in one direction to move said tub into successive positions, a pair of spaced levers pivotally supported beneath said bar and having serrated ends extending above said bar and swingable above said rails in one of said positions, a cross connection between said levers, a lug 50 on said bar adapted to engage said cross connection and swing said lever ends into contact with said bottom during the tub-advancing movement of said bar whereby said bottom is moved into laterally spaced 55 relation to said tub, and elevating means for seating said bottom.
- 60 20. In apparatus of the class described having a support for an assembly of staves with a bottom seated therein and with a 65 hoop supported adjacent the ends thereof, the combination of a reciprocatory clamping head having movable jaws adapted to enclose said hoop and said stave ends in the movement of said clamping head, a reciprocatory cross head supporting said clamping 70 head, a driven shaft, crank means on the shaft, a driving connection from said crank means to said cross head, a ring slidably mounted on said jaws and operable to contract said jaws, operating rods attached to 75 said ring and slidably supported on said cross head, bearing members carried by said rods, and cam means on said shaft adapted to operatively engage said bearing members thereby causing said jaws to be contracted 80 into engagement with said staves and said hoop during the said enclosing movement thereof and effecting the compression of said stave ends and the seating of said hoop 85 thereover.
21. In apparatus of the class described having a support for an assembly of staves with a bottom seated therein and with a hoop supported adjacent the ends thereof, the combination of a reciprocatory clamping 90 head having movable jaws adapted to enclose said hoop and said stave ends in the movement of said clamping head, a reciprocatory cross head supporting said clamping head, a driven shaft, crank means on the shaft, a driving connection from said crank means to said cross head, a ring slidably mounted on said jaws and operable to contract said jaws, operating rods attached to 95 said ring and slidably supported on said cross head, bearing members carried by said rods, said bearing members being adjustable on said rods to vary the normal position of said ring relative to said jaws, and cam means on said shaft adapted to operatively 100 engage said bearing members, thereby causing said jaws to be contracted into engagement with said staves and said hoop during the said enclosing movement thereof and effecting the compression of said stave ends 105 and the seating of said hoop thereover.
22. In apparatus of the class described, in combination, a clamping head for compressing the stave ends of a tub or the like and seating a hoop thereupon comprising a center support, an annular series of segmental jaws mounted on said support and radially movable thereon, resilient means tending to maintain said jaws in outer position, said jaws having depending angular stave clamping portions collectively forming a segmental flange with outwardly tapered inner and outer peripheries and with an inner annular hoop receiving recess terminating upwardly in a hoop driving shoulder, a ring 110 slidably mounted on the outer periphery of the flange portion of said series of jaws adapted by downward movement to contract said jaws into engagement with said stave ends and said hoop, means for moving said 115
- 120 125 130

clamping head into encircling relation to said stave ends and said hoop, and means for moving said ring to contract said jaws intermediately of the limits of said encircling movement.

23. In apparatus of the class described, means for supporting a hoop adjacent the stave ends of a tub or the like comprising a contractable ring adapted to abut the said stave ends and carry a hoop on its outer periphery, and a contractable guide band within said ring having an edge extending outwardly therefrom to enter within said stave ends.

24. In apparatus of the class described, a hoop support comprising a split ring adapted to carry a hoop on its outer periphery, a split band loosely positioned within said ring having an edge extending outwardly therefrom, inwardly bent spaced end portions on said band, and a plurality of radial

guide pins fixed in said ring and passing freely through said band.

25. In apparatus of the class described, in combination, means for slidably supporting 25 an inverted bottomless tub and a bottom loosely positioned therein, means for moving said tub and enclosed bottom along said supporting means into position to be operated upon, and a lever positioned adjacent 30 the path of said bottom having a serrated end swingable into engagement with said bottom, said lever being operable by said tub moving means to accelerate the movement of said bottom and position the same 35 centrally of said tub when in position to be operated upon.

In witness whereof we have hereunto set our hands.

WALTER M. PAULSON.
AXEL M. WALSTROM.
